CLAIM

I claim the ornamental design for a light indicator, as shown and described.

DESCRIPTION

FIG. 1 is a rear bottom perspective view of a light indicator of the present disclosure;

FIG. 2 is a front elevational perspective view of the light indicator of FIG. 1;

FIG. 3 is a rear elevational view of the light indicator of FIG. 1;

FIG. 4 is a bottom plan view of the light indicator of FIG. 1;

FIG. 5 is a top plan view of the light indicator of FIG. 1;

FIG. 6 is a left side elevational view of the light indicator of FIG. 1; and,

FIG. 7 is a right side elevational view of the light indicator of FIG. 1.

The broken lines illustrate environmental structure that forms no part of the claimed design.
